UNITED STATES PATENT OFFICE.

WALTER R. DENMAN, OF CLEVELAND, OHIO.

DESIGN FOR A TIRE.

Application filed May 23, 1922. Serial No. 2,385. Term of patent 3½ years.

To all whom it may concern:

Be it known that I, WALTER R. DENMAN, a citizen of the United States, residing at Cleveland, in the county of Cuyahoga, State of Ohio, have invented a new, original, and ornamental Design for Tires, of which the following is a specification, reference being had to the accompanying drawing, forming part thereof, in which:

Figure 1 is a plan view of a portion of a tire showing the new design; and

Figure 2 is a sectional elevation taken on the line 2—2 of Figure 1.

I claim as my invention:
The ornamental design for a tire as shown.

WALTER R. DENMAN.
